Primary Examiner — Ricky Pham*(74) Attorney, Agent, or Firm* — Tucker Ellis LLP; Carlos Garritano(57) **CLAIM**

The ornamental design for a square baking pan, as shown and described.

DESCRIPTION

FIG. 1 is a top perspective view of an embodiment of the square baking pan.

FIG. 2 is a front view thereof, the opposite rear view being a mirror image thereof

FIG. 3 is a side view thereof, the opposite side view being a mirror image thereof

FIG. 4 is top view thereof.

FIG. 5 is a bottom view thereof.

FIG. 6 is a partial side cross section view taken along line 6-6 of FIG. 4; and,

FIG. 7 is a partial front cross section view taken along line 7-7 of FIG. 4.

The evenly-spaced broken lines in the drawings are included for purpose of illustrating portions of the square baking pan that form no part of the claimed design. The dot-dash-dot broken lines in the drawings are included for the purpose of defining the boundary of the claim, it being understood that the dot-dash-dot broken lines themselves form no part of the claimed design.
